UNITED STATES PATENT OFFICE.

JAMES E. WILLIAMSON, OF PITTSBURGH, PENNSYLVANIA, ASSIGNOR OF ONE-HALF TO
HENRY F. LUEBBE, OF PITTSBURGH, PENNSYLVANIA.

ELECTRIC WELL HEATER.

Application filed February 23, 1923. Serial No. 620,757.

To all whom it may concern:

Be it known that I, JAMES E. WILLIAMSON, a citizen of the United States, residing at Pittsburgh, in the county of Allegheny 5 and State of Pennsylvania, have invented certain new and useful Improvements in Electric Well Heaters, of which the following is a specification.

This invention relates to new and useful 10 improvements in electric well heaters adapted to be lowered into an oil-well and therein heated by electric current generated at the surface.

Important objects of this invention are to 15 provide a heater of the type stated, in a manner as hereinafter set forth, which will function to soften and liquefy the congealed, solid, and semi-solid products of petroleum occurring in oil-wells after a period of pro- 20 longed pumping and which obstruct the natural flow of oil, thereby restoring the normal oil production of the well; which pro- 25 vides for the contraction and expansion of the heater parts subjected to varying temperatures; and which embodies multiple electric heating units and check elements for augmenting the efficiency of the apparatus.

Further objects of this invention are to 30 provide an electric heater of the class de- scribed, which is simple in its construction and arrangement, strong, durable and effi- 35 cient in its use, compact, and comparatively inexpensive to manufacture and operate.

With the foregoing and other objects in 35 view, which will appear as the description proceeds, the invention resides in the combination and arrangement of parts hereinafter described and claimed, it being understood that changes in the precise embodiment of 40 the invention herein disclosed can be made within the scope of what is claimed without departing from the principle of the invention.

In the drawing forming a portion of this 45 specification and wherein like numerals of reference designate corresponding parts throughout the several views:—

Figure 1 is a vertical sectional view of an 50 electric heater in accordance with this invention.

Figures 2 and 3 are enlarged detail views of the upper and lower check valves, respectively, with associated parts, shown in cross section.

Referring in detail to the drawing, the 55 heater comprises a body portion consisting of an elongated cylindrical casing 1 provided with a top cap 2 and a bottom cap 3. The caps 2 and 3 have a screw thread connection with respective ends of the casing 1, 60 and have their outer peripheral surfaces disposed to extend flush with the outer periphery of the casing 1, for the purpose of establishing an uninterrupted outer surface throughout the length of the body portion to facilitate the travel of the heater when being lowered into the well or when being elevated therefrom.

Disposed centrally in the casing 1 is a vertically extending tube 4, which has its upper end threadably secured, as at 5, in the top cap 2. The lower end of the tube 4 projects through the stuffing box 6 which is formed in the bottom cap 3. The stuffing box 6 is provided with a gland nut 7, of the usual construction, which when properly adjusted in the former with suitable packing 8, will establish an impervious shiftable connection with the tube 4, permitting of expansion and contraction of associated parts subjected to varying temperatures during the 75 operation of the heater.

A comparatively short pipe 9, of less diameter than the tube 4 but communicating with the latter through the port 24 formed in the valve seat 25, is threadably connected, as at 10, to the top cap 2 and projects upwardly therefrom. A foraminous member, consisting of a hollow metal ball 11, is fixed to the upper end of the pipe 9 and communicates therewith. The ball 11 is formed with a plurality of small perforations 12 for the purpose to be described. The top portion of the ball 11 is formed with a suitable aperture 13 adapted for securing the supporting cable 14 therein. The aperture 13 does not communicate with the interior of the hollow ball 11 but extends transversely through the solidly formed top portion thereof.

The entire length of the tube 4 within the casing 1, with the exception of its upper portion 15 and its lower portion 15', is covered with suitable insulation 16, upon which is coiled the resistance wire in a manner to provide the multiple heating series 17 and 18. The electrical energy is supplied from its source by the supply conductor 19,

which enters the casing through an imperviously mounted insulator 20 in the top cap 2.

The lower terminus of the coil forming 5 the heating unit 17 is connected, as at 21, to the conductor 19, while the upper end thereof is grounded on the upper portion 15 of the tube 4 through the contact 22. The upper end of the coil forming the heating 10 unit 18, connects with the conductor 19, as indicated at 23, and the lower terminus thereof is grounded on the lower portion 15' of the tube 4 through the contact 26.

The winding arrangement of the heating 15 element in multiple series as above described will not only save the insulation on the supply or positive conductor 19 by using low voltage and high amperage, but will give high resistance between the positive 20 conductor 19 and the negative conductor, which latter is the supporting cable 14 and is connected with the electrical generator during the operation of the heater. While the multiple series heating element is illustrated as comprising but two units it will 25 be obvious that any number may be employed to best meet conditions found in practice.

A check valve 27 is mounted in the lower 30 projecting end of the tube 4 and co-operates with the valve seat 28, formed in the reducer bushing 29. The latter is threadably connected with the tube 4 and carries a depending reduced intake nipple 30. The 35 function of the check valve 27 is to permit of the entrance of the fluid into the tube 4 only after it has reached a predetermined temperature.

A similar check valve 31 is mounted in 40 the pipe 9 on the top cap 2 and co-operates with the valve seat 25, formed in the top cap 2. The check valve 31 is preferably regulated to permit of the escape of the fluid from the tube 4, only after the fluid 45 has been vaporized.

A plurality of insulating collars 32 is fixedly mounted on the tube insulation 16. These collars 32 are spaced from each other and are provided for the purpose of guarding 50 the multiple heating series 17 and 18 from possible contact with the inner wall of the casing 1.

In practice my improved heater is lowered into an oil-well by the supporting 55 cable 14. When the device has been intensely heated by the current generated at the surface, the congealed products of petroleum surrounding the heater will be liquidized. Upon attaining a certain temperature 60 the heated liquid will operate the valve 27 and pass upwardly into the tube 4 through the nipple 30. In its passage through the tube 4 the liquid will be vaporized and forced through the valve 31 and be diffused into the area surrounding

the heater by its passage through the perforated ball 11. The vaporization of the liquid will augment the efficiency of the heater and expedite the operation of liquidizing the congealed petroleum products.

What I claim is:

1. An electric heater for the purpose set forth comprising an elongated cylindrical casing, a top cap threadably connected to the upper end of said casing, a bottom cap threadably connected to the lower end of said casing, a fluid conductor extending vertically through said casing and threadably engaging said top cap and shiftably engaging said bottom cap, a multiple series electrical heating element carried by said conductor, means for supplying electrical current to said element, and a pair of check valves carried by said conductor for retarding the passage of the fluid through said conductor, and a foraminous hollow member fixed to the upper end of said conductor for diffusing the fluid when expelled from said conductor.

2. An electric heater for the purpose set forth comprising an elongated cylindrical casing, a top cap threadably connected to 75

the upper end of said casing, a bottom cap threadably connected to the lower end of said casing, a fluid conductor extending vertically through said casing and threadably engaging said top cap and shiftably engaging said bottom cap, a multiple series electrical heating element carried by said conductor, and means for supplying electrical current to said element, and a pair of check valves carried by said conductor for retarding the passage of the fluid through said conductor, and a foraminous hollow member fixed to the upper end of said conductor for diffusing the fluid when expelled from said conductor.

2. An electric heater for the purpose set forth comprising an elongated cylindrical casing, a top cap threadably connected to the upper end of said casing, a bottom cap threadably connected to the lower end of said casing, a fluid conductor extending vertically through said casing and threadably engaging said top cap and shiftably engaging said bottom cap, a multiple series electrical heating element carried by said conductor, and means for supplying electrical current to said element, the peripheral surfaces of said top and bottom caps being flush with the peripheral surface of said casing.

3. An electric heater for the purpose set forth comprising an elongated cylindrical casing, a top cap threadably connected to 105

the upper end of said casing, a bottom cap threadably connected to the lower end of said casing, a fluid conductor extending vertically through said casing and threadably engaging said top cap and shiftably engaging said bottom cap, a multiple series electrical heating element carried by said conductor, and means for supplying electrical current to said element, the peripheral surfaces of said top and bottom caps being flush with the peripheral surface of said casing.

3. An electric heater for the purpose set forth comprising an elongated cylindrical casing, a top cap threadably connected to the upper end of said casing, a bottom cap threadably connected to the lower end of said casing, a fluid conductor extending vertically through said casing and threadably engaging said top cap and shiftably engaging said bottom cap, a multiple series electrical heating element carried by said conductor, and means for supplying electrical current to said element, the peripheral surfaces of said top and bottom caps being flush with the peripheral surface of said casing.

4. An electric heater for the purpose set forth comprising an elongated cylindrical casing, a top cap threadably connected to 110

the upper end of said casing, a bottom cap threadably connected to the lower end of said casing, a fluid conductor extending vertically through said casing and threadably engaging said top cap and shiftably engaging said bottom cap, a multiple series electrical heating element carried by said conductor, and means for supplying electrical current to said element, the peripheral surfaces of said top and bottom caps being flush with the peripheral surface of said casing.

4. An electric heater for the purpose set forth comprising an elongated cylindrical casing, a top cap threadably connected to the upper end of said casing, a bottom cap threadably connected to the lower end of said casing, a fluid conductor extending vertically through said casing and threadably engaging said top cap and shiftably engaging said bottom cap, a multiple series electrical heating element carried by said conductor, and means for supplying electrical current to said element, the peripheral surfaces of said top and bottom caps being flush with the peripheral surface of said casing.

conductor, means for supplying electrical current to said element, and a pair of check valves carried by said conductor for retarding the passage of the fluid through said conductor, the peripheral surfaces of said top and bottom caps being flush with the peripheral surface of said casing.

5. An electric heater for the purpose set forth comprising an elongated cylindrical casing, a top cap threadably connected to the upper end of said casing, a bottom cap threadably connected to the lower end of said casing, a fluid conductor extending vertically through said casing and threadably engaging said top cap and shiftably engaging said bottom cap, a multiple series electrical heating element carried by said conductor, and means for supplying electrical current to said element, and a foraminous hollow member fixed to the upper end of said conductor for diffusing the fluid when expelled from said conductor, the peripheral surfaces of said top and bottom caps being flush with the peripheral surface of said casing.

6. An electric heater for the purpose set forth comprising an elongated cylindrical casing, a top cap threadably connected to the upper end of said casing, a bottom cap threadably connected to the lower end of said casing, a fluid conductor extending vertically through said casing and threadably engaging said top cap and shiftably engaging said bottom cap, a multiple series electrical heating element carried by said conductor, and means for supplying electrical current to said element, means for retarding the movement of the fluid through said conductor, and a foraminous hollow member fixed to the upper end of said conductor for diffusing the fluid when expelled from said conductor, the peripheral surfaces of said top and bottom caps being flush with the peripheral surface of said casing.

7. An electric heater for the purpose set forth comprising an elongated cylindrical casing, a top cap threadably connected to the upper end of said casing, a bottom cap threadably connected to the lower end of said casing, a fluid conductor extending vertically through said casing and threadably engaging said top cap and shiftably engaging said bottom cap, a multiple series electrical heating element carried by said conductor, means for supplying electrical

current to said element, and a pair of check valves carried by said conductor for retarding the passage of the fluid through said conductor, and a foraminous hollow member fixed to the upper end of said conductor for diffusing the fluid when expelled from said conductor, the peripheral surfaces of said top and bottom caps being flush with the peripheral surface of said casing.

8. An electric heater for the purpose set forth comprising a closed hollow casing, a fluid conductor extending through said casing, an electric heating element mounted on said conductor, and means associated with said conductor for vaporizing said fluid on its passage through said conductor, and means for supplying electrical current to said element.

9. An electric heater for the purpose set forth comprising a closed hollow casing, a fluid conductor extending through said casing, an electric heating element mounted on said conductor, means for supplying electrical current to said element, and check valves mounted on said conductor for retarding the movement of the fluid through said conductor for vaporizing the fluid on its passage through said conductor.

10. An electric heater for the purpose set forth comprising a closed hollow casing, a fluid conductor extending through said casing, an electric heating element mounted on said conductor, means for supplying electrical current to said element, and means associated with said conductor for vaporizing said fluid on its passage through said conductor, and a foraminous member mounted on the top of said conductor for diffusing the vaporized fluid when expelled from said conductor.

11. An electric heater for the purpose set forth comprising a closed hollow casing, a fluid conductor extending through said casing, an electric heating element mounted on said conductor, means for supplying electrical current to said element, check valves mounted on said conductor for retarding the movement of the fluid through said conductor for vaporizing the fluid on its passage through said conductor, and a foraminous member mounted on the top of said conductor for diffusing the vaporized fluid when expelled from said conductor.

In testimony whereof I affix my signature.
JAMES E. WILLIAMSON.
